GOLF CLUB

Eugene H. Lesch, 5702 E. St. Andrews Way,
Scottsdale, Ariz. 85254

Filed Apr. 29, 1970, Ser. No. 22,699

Term of patent 14 years

Int. Cl. D21—02

U.S. Cl. D34—5

FIG. 1 is a perspective view of a golf club embodying my new design.

FIG. 2 is a toe end elevation of the golf club head.

FIG. 3 is a side elevation of the golf club head looking toward the striking face.

FIG. 4 is a side elevation of the golf club head looking toward the following side.

FIG. 5 is a shaft end elevation of the golf club head.

The shaft is shown fragmentarily in FIGS. 2 through 5 for convenience of illustration.

I claim:

The ornamental design for a golf club, as shown and described.
